BOTTLE HOLDER

Joseph B. Biederman, Cincinnati, Ohio

Application April 24, 1953, Serial No. 350,889

5 Claims. (Cl. 294—87.2)

This invention relates to a rack for bottles and more particularly, to a rack which may be used as a bottle carrier and as a device for hanging bottles from a stationary support.

An object of this invention is to provide a rack having a handle by means of which the rack can be carried and by means of which the rack can be hung or suspended from a stationary support with bottles mounted on the rack.

A further object of this invention is to provide a rack by which bottles may be suspended therefrom by the necks thereof.

A further object of this invention is to provide a rack having an elongated main member of substantially inverted U-shape in section from end to end which forms a way for the necks of bottles having rolled lips, in which rack the flanges of the main member extend toward but in spaced relation to each other so that the bottles may be suspended by the lips thereof.

A further object of this invention is to provide a rack support for such a rack to which the rack may quickly and easily be attached, or from which the rack may readily be removed.

A further object of this invention is to provide a latching means for holding the rack on the rack support.

From the following description and the accompanying drawing, the above and other objects and features of the invention will be apparent to those having ordinary skill in the art to which it pertains.

In the drawing:

Figure 1 is a view in side elevation showing a rack constructed in accordance with an embodiment of this invention, two bottles being suspended from the rack;

Fig. 2 is a view in section taken along a line II—II in Fig. 1;

Fig. 3 is a fragmentary top plan view of the rack, part of the handle thereof being broken away and in section for clarity of detail;

Fig. 4 is a fragmentary view in bottom plan of a portion of the rack;

Fig. 5 is a plan view of a rack and rack support constructed in accordance with another embodiment of this invention, the latch of the rack support being partly broken away for clarity;

Fig. 6 is a view in section taken along a line VI—VI in Fig. 5; and

Fig. 7 is a fragmentary view in section taken along a line VII—VII in Fig. 3.

In the following detailed description, and the drawing, like reference characters indicate like parts.

As shown in Figs. 1 and 2, the rack includes an elongated member 10 of substantially inverted U-shape in section from end to end. The lower edges of flanges 12 and 13 of the member 10 are turned inwardly towards but spaced from each other to form edge flanges 14 and 16. The flanges 14 and 16 form a way for the necks of bottles 17.

As shown in the drawing, each bottle 17 has a neck 18 and a rolled lip or bead 19. The lips of the bottles rest on the edges of the flanges 14 and 16 so that the bottles are suspended from the flanges.

Bottle stops 21 and 22 are provided at the ends of the elongated member 10. The stop 21 is U-shaped in general outline and is provided with inwardly projecting prongs 22' and 23 at the ends thereof. The prongs 22' and 23 are received in openings in the flanges of the elongated member 10.

The stop member 21 is formed of resilient metal, and is provided with a looped or bent portion 24 that is en-

2

gageable with one of the flanges of elongated member 10 so that the stop member 21 will stay in the raised position shown in Fig. 1. In addition, the member 21 may be swung downwardly to a position similar to that in which the member 22 is shown. When the members 21 and 22 are swung downwardly, they serve as stops to retain the bottles in the way of the elongated member.

A U-shaped handle 26 is attached to the web of member 10 substantially centrally thereof. The arms of the handle 26 are provided with shoulders 27 (Fig. 7) which engage the web of member 10. The ends of the arms project through the web and are peened over, as shown in Fig. 4, at 28 to firmly hold the ends of the handle in assembly with the web of the elongated member 10.

As shown most clearly in Figs. 1 and 3, the handle 26 fits over a U-shaped supporting bracket 29. As shown in Figs. 2 and 3, the bracket 29 is attached to a wall 31 or the like and projects outwardly therefrom in substantially a horizontal plane. The arms of the bracket 29 are provided with Z-shaped bends 32 which engage the handle 26. Similarly, the handle 26 is provided with substantially Z-shaped bends 33 which engage the bracket.

The rack is held in position on the bracket 29 by means of a resilient latch member 34. The latch member 34 is rigidly attached to the cross member 36 of the bracket and extends, cantilever-fashion, therefrom toward wall 31. A U-shaped portion or tongue 37 on the lower side of latch member 34 engages a slot 38 in the web of elongated member 10 to hold the rack in position on the rack-supporting bracket 29. As shown in Fig. 2, a portion of the latch member 34 extends beyond U-shaped portion 37 to form a tongue 41. The tongue 41 is adapted to engage one of the flanges of the rack when the rack is pushed onto the rack support and raise the latching portion 37 so that it can fall into the slot 38. In addition, the tongue 41 may be engaged to raise the latch 34 from the web of the elongated member of the rack to release the rack. A return bend portion 42 of the latch overlies the main portion and serves as a stop to limit upward movement of the latch member 34. The return bend portion 42 and the main portion of the latch 34 are held together by a rivet 43. The rivet 43 extends into a groove 46 in the cross member of the bracket to lock the latch member thereto.

The rack illustrated in Figs. 5 and 6 is similar to that shown in the other drawings with the exception that a different form of latch member 50 is employed. The latch member 50 is pivotally mounted in a rack-supporting bracket 51. The latch includes a U-shaped main member 52 which extends around the rack-supporting bracket. A plug 53 of plastic material is disposed between the arms of the U-shaped member 52 and is attached thereto by means of a rivet 54.

The elongated member 10 of the rack is formed of metal, for example, aluminum, and the plug 53 is formed of the methyl methacrylate resin of the type commonly referred to as Lucite Plexiglas. When the latch member 52 is swung downwardly to the position shown in Fig. 6 the resinous plug engages one of the flanges of the elongated member to lock the rack member 10 upon the rack-supporting bracket. On the other hand, when the latch member 50 is swung upwardly to the position shown in dotted lines, the rack is released and can be removed from the bracket 51.

The racks illustrated in the drawing may be used by a delivery man delivering milk, soft drinks, or the like. The bottles are supported in the rack by the necks thereof and may readily be carried by means of the handles of the racks. The bottles do not need to be removed from the racks when delivered, but the racks may simply be inserted into an appropriate mounted rack support without need for moving or adjusting the bottles in the racks.

The racks illustrated in the drawing and described above are subject to structural modification without departing from the spirit and scope of the appended claims.

Having described my invention, what I claim as new and desire to secure by Letters Patent is:

1. A rack for bottles having a neck and a rolled lip comprising an elongated member of substantially inverted

U-shape in section from end to end, the edges of the flanges of said member extending inwardly towards but spaced from each other to provide a way for the necks of the bottles, the lips of the bottles bearing on said flange edges, whereby the bottles are suspended from the flanges, bottle stop means at the ends of the elongated member for retaining the bottles therein, a U-shaped handle attached to the web of the elongated member, a U-shaped rack support adapted to be removably received between the arms of the handle, the handle and rack support being engageable, and a latch member mounted on the cross member of the rack support to engage the elongated member and hold the handle and rack support in engagement.

2. A rack in accordance with claim 1 characterized by the fact that the elongated member is slotted between the arms of the handle, that the latch member is resilient and is rigidly attached to the rack support, and that a tongue on the latch member is releasably received in the slot to hold the handle on the rack support.

3. A rack in accordance with claim 1 characterized by the fact that the latch member is pivotally mounted on the cross member of the rack support and that the latch member releasably engages one of the flanges on the main portion.

4. A rack in accordance with claim 1, characterized by the fact that the latch member is pivotally mounted on the cross member of the rack support, that the elongated member is formed of metal, that the latch member includes a plug of plastic resinous material, and that the plug of the latch member releasably engages one of the flanges of the main portion.

5. A rack for bottles having a neck and a rolled lip

comprising an elongated member of substantially inverted U-shape in section from end to end, the edges of the flanges of said member extending inwardly towards but spaced from each other to provide a way for the necks of the bottles, the lips of the bottles bearing on said flange edges, whereby the bottles are suspended from the flanges, bottle-stop means at the ends of the elongated member for retaining the bottles therein, a U-shaped handle attached to the web of the elongated member, a U-shaped rack support adapted to be removably received between the arms of the handle, the handle and the rack support being engageable, a resilient latch member rigidly attached cantilever-fashion to the cross member of the rack support, there being a latch actuating tongue on the latch member, said latch actuating tongue being engageable with one of the main flanges of the elongated member when the handle is advanced over the rack support to swing the free end of the latch member upwardly, and latch keeper means on the main portion engageable with the latch to hold the handle and rack support in engagement.
